(21) Appl. No.: **29/231,952**

(57) **CLAIM**

(22) Filed: **Jun. 13, 2005**

The ornamental design for a rotating aerator for aquariums and ponds, as shown and described.

(30) **Foreign Application Priority Data**

Dec. 13, 2004 (IT) VE2004O0012

(51) **LOC (9) Cl.** **23-01**

DESCRIPTION

(52) **U.S. Cl.** **D23/210; D30/106**

FIG. 1 is a top view of an embodiment of the aerator of the present invention.

(58) **Field of Classification Search** D23/210,
D23/214; D30/106; 261/93, 122.1; 119/263;
210/167.23, 167.26

FIG. 2 is a front view of the embodiment of the present invention.

See application file for complete search history.

FIG. 3. is a bottom view of the embodiment.

(56) **References Cited**

FIG. 4 is a rear view of the embodiment.

U.S. PATENT DOCUMENTS

FIG. 5 is a side view of the embodiment; and,

2,788,170 A * 4/1957 Kato et al. 417/413.1
2,942,772 A * 6/1960 Buchanan 417/413.1
